UNITED STATES PATENT OFFICE.

ROBERT F. KENYON, OF SAN FRANCISCO, CALIFORNIA.

RADIO RECEIVER.

Application filed March 7, 1925. Serial No. 13,872.

The present invention relates to improvements in radio receivers and has particular reference to a crystal receiver and to mounting means of the electrode, commonly known as the "cat's whiskers," relative to the crystal.

It is proposed to provide in the present invention an arrangement particularly adapted for installation in the conventional type of radio panel because the mounting means allows of a setting of the movable electrode relative to the crystal by means of a knob which may be presented on the outside of the panel in the manner now generally adopted for the setting of all the other variable elements in a radio set.

It is furthermore proposed in the present invention to provide mounting means for the movable electrode of a crystal set that will insure perfect contact between the electrode and the crystal and that will positively maintain the contact until released by the operator.

It is further proposed to provide a movement for the electrode that allows of very delicate adjustment and particularly allows the tension between the electrode and the crystal to be arranged for best results.

Further objects and advantages of my device will appear as the specification proceeds.

The preferred form of my invention is illustrated in the accompanying drawing, in which

Figure 1 shows a front view of a panel having my radio receiving arrangement attached thereto.

Figure 2 a section taken along line II-II of Figure 1.

Figure 3 a section taken along line III-III of Figure 2, and

Figure 4 a rear view of the device illustrated in Figure 3.

While I have shown only the preferred form of the invention, it should be understood that various changes or modifications may be made within the scope of the claims hereto attached without departing from the spirit of the invention.

The panel 1 which is preferably made of "bakelite" may be considered the front wall of a conventional box for a radio receiving set. My particular arrangement includes a second panel 2 preferably made of rectangular form, as shown in Figures 3 and 4, and formed with a perforation 3 through which

extends the sleeve 4 which is held relative to the panel by means of two nuts 6 and 7 threaded upon the sleeve on opposite sides of the panel. The panel 2 may be secured in parallel relation to the panel 1 by means of a third nut 8 threaded upon the end of the sleeve extending through a perforation 9 in the main panel 1. A rod or pin 11 of considerably smaller diameter than the bore of the sleeve extends through the latter and is provided at one end with a nut 12 and a knob 13 with a washer 14 bearing on one end of the sleeve and a second washer 16 bearing on the other end of the sleeve, while a coiled spring 17 encircling the pin 11 bears on the washer 16 and thereby exercises a clamping action which holds the pin in place but allows the same to be manually shifted within the bore of the sleeve. The free end of the spring 17 bears on a washer 18 and through the same on a lever 19 fulcrumed to the pin with a nut 21 threaded on the extreme end of the pin and preventing the lever from being pushed off by the spring 17. The bottom face 22 of the nut 21 is cut on a slant so that the nut acts like a cam which cooperates with the spring 17 in imparting a rocking motion to the lever 19 when the pin 11 is revolved by means of the knob 13.

The crystal 23 is held in a cup 24 by means of a set screw 26 and the cup 24 is secured in the panel 2 by the screw 27. One of the ends 28 of the lever 19 extends over the crystal 23 and has a coiled spring 29 lying thereon with one end of the spring secured to a remote point of the lever by means of the screw 31, while the other end extends through a perforation 32 near the extreme end of the lever and forms a straight electrode 33 pointing toward the crystal 23 and engaging the same when the lever is rocked, so that the end 28 of the lever slants toward the panel 2.

The other or rear end of the lever is formed with a slot 34 through which extends a guide pin 36, one end of which is secured to the panel 2 by means of two nuts 37 and 38, this engagement serving to limit the revolving motion of the lever 19 substantially to the area of the crystal 23.

Suitable terminals 41 and 42 extend from the screw 27 and the guide pin 36 respectively, the guide pin 36 being electrically connected to the sleeve 4 by means of the leaf spring 43.

The operation of my device will be readily

understood from the foregoing description. The lever 19 may be rocked for engagement of the electrode 33 with the crystal and for disengagement of the two by turning the 5 knob 13, the cam face 22 of the nut 21 cooperating with the spring 17 in effecting such rocking motion. To shift the electrode 33 from its position preferably after it has been lifted out of engagement with the crystal, it is only necessary to shift the pin 11 in the bore of the sleeve 4 which allows the electrode 33 to be shifted to any point desired, the electrode being substantially limited to the area of the crystal by the engagement of 10 the pin 36 with the rear end of the lever 19.

After engagement between the electrode 33 and a sensitive point of the crystal has been established, the tension between the 15 points of the contact may be increased or relaxed by turning the knob 13 for increasing or decreasing the distance between the crystal and the lever and for increasing and decreasing respectively the tension of the coiled spring 29.

25 I claim:

1. In a radio receiver, a crystal, an electrode, and mounting means for the electrode allowing the electrode to be selectively engaged with and disengaged from the crystal, comprising a rotatable pin, a lever fulcrumed thereon extending over the crystal with one end thereof and having the electrode associated with the said end and means for allowing the lever to be rocked on 30 its fulcrum for effecting engagement or disengagement respectively of the electrode with the crystal.

2. In a radio receiver, a crystal, an electrode and mounting means for the electrode allowing the latter to be selectively engaged with and disengaged from the crystal, and comprising an operating element and a lever fulcrumed thereon extending over the crystal with one end thereof and having the 35 electrode secured to the said end, the operating element having means associated therewith for effecting a rocking motion of the lever when the operating element is turned.

3. In a radio receiver, a crystal, an electrode and mounting means for the electrode allowing the latter to be selectively engaged with and disengaged from the crystal and comprising an operating element and a lever fulcrumed thereon extending over the crystal with one end thereof and having the electrode secured to the said end, the operating element having a cam and spring means thereon engaging the lever from opposite sides for effecting a rocking motion of the 40

lever when the operating element is turned. 60

4. In a radio receiver, a crystal, an electrode and mounting means for the electrode allowing the electrode to be selectively engaged with any point of the crystal, comprising an operating element, a lever fulcrumed thereon extending over the crystal with one end thereof and having the electrode fixed to the said end, means allowing the lever to be rocked by a turning motion of the operating element and means allowing 65 the operating element to be shifted. 70

5. In a radio receiver, a crystal, an electrode and mounting means for the electrode allowing the electrode to be selectively engaged with any point of the crystal, comprising an operating element, a lever fulcrumed thereon extending over the crystal with one end thereof and having the electrode fixed to the said end, means allowing the lever to be rocked by a turning motion of 75 the operating element and means allowing the operating element to be shifted in combination with means for confining the resulting shifting of the operating end of the lever substantially to the area of the crystal. 80

6. In a radio receiver, a panel formed with a perforation therein, a pin extending through the perforation with freedom of lateral shifting, spring means yieldingly opposing such shifting, a lever pivoted to the pin and a cam on the pin cooperating with the spring means for holding the lever and for imparting rocking motion to the latter when the pin is turned. 90

7. In a radio receiver, a panel formed with a perforation therein, a pin extending through the perforation with freedom of lateral shifting, spring means yieldingly opposing such shifting, a lever pivoted to the pin and a cam on the pin cooperating with the spring means for holding the lever and for imparting rocking motion to the latter when the pin is turned, with guide means for one end of the lever limiting the motion of the other end. 95

8. In a radio receiver, a panel formed with a perforation therein, a pin extending through the perforation with freedom of lateral shifting, spring means yieldingly opposing such shifting, a lever pivoted to the pin and a cam on the pin cooperating with the spring means for holding the lever and for imparting rocking motion to the latter when the pin is turned, one end of the lever being slotted and a guide pin extending through the slot for limiting the motion of 100 the other end of the lever. 105
